UNITED STATES PATENT OFFICE.

WALTER H. LENISH, OF CHICAGO, ILLINOIS.

ROLLER SCREEN.

Application filed September 12, 1927. Serial No. 218,882.

My invention relates to rolling screens particularly to that type in which a screen is rolled up on a roller within a casing at the upper end of the window frame and adapted to be drawn downwardly to the window sill to close the window opening.

One important object of the invention is to provide improved concealed latching means, inaccessible from the outside of the closed screen, for locking the screen automatically in closed position when the screen is moved to such a position.

Another important object is to adapt the latching mechanism to be released by a slight axial turn of the screen rail bar.

Another important object is to provide finger grips or lifts at the ends of the rail bar which, under upward pressure preparatory to raising the screen, will first twist or rotate the rail bar to cause unlatching of the screen.

Another important object is to provide simple means for adjusting the latch structure.

The above and other features of my invention are incorporated in the structure shown on the drawings, in which

Fig. 1 is a front view of a window frame showing the general arrangement of my improved screen structure.

Fig. 2 is an enlarged front view of a corner of the window frame and the screen structure,

Fig. 3 is an enlarged section on plane 3—3

Fig. 1,

Fig. 4 is a section on plane 4—4 Fig. 3,

Fig. 5 is a section on plane 5—5 Fig. 3, showing the latched position of the parts.

Fig. 6 is a similar section showing the unlatched position,

Fig. 7 is a perspective view showing a modified arrangement of latch plate and spring.

Fig. 8 is a transverse section showing the operation of the modified arrangement in the guide channels, and

Fig. 9 is a section on plane 9—9 Fig. 8.

On Fig. 1 the screen S is shown applied to a window frame F, the screen being mounted on a roll housed in the receptacle B mounted

at the top of the window frame, as, for example, in the manner disclosed in my co-pending application Serial No. 149,849, filed November 22, 1926. The outer end of the screen is secured to a rail bar structure R 55 which at its ends engages in guide structures G and G' secured against the sides of the window frame.

The rail bar structure shown comprises the two clamping strips 10 and 11 of sheet metal and having the strengthening and stiffening ribs 12 adjacent to their longitudinal edges. The strips receive between them the lower end of the screen S and are secured together by bolts 13 to clamp the screen. 60 A sealing strip 14 which may be of felt is interposed between the screen and the inner clamping strip 11 and engages against the window sill when the screen is pulled down.

Referring first to the arrangement shown 70 in Figs. 1 to 6, at each end of the rail bar structure guide plates 15 and 16 are interposed between the clamping strips and the screen. At each end of the rail bar, on the inner side thereof, is applied a finger grip 75 or lift 17, by means of which the rail bar, and, consequently, the screen, may be readily raised and lowered. The projecting ends 16' of the guide plate 16 are straight, while the projecting ends 15' of the plate 15 are 80 deflected, as clearly shown in Fig. 3, and these ends engage in the guide structures G and G' in a manner to be now described.

The guide structures G and G' are shown 85 as each comprising the guide strips 18 and 19 spaced apart to form the guide channel 20. The guide strips are of L-shape and are secured with their base sections against the window frame jamb and between inner and outer stops 21 and 22 secured against the 90 jams, these stops overlying the base sections of the guide strips and abutting against the guide strip body, as clearly shown. The strips along their outer edges are deflected diagonally as indicated at 18' and 19', with the outer edges separated to leave the entrance or guide slots 23 leading to the channels 20 and in which the guide plates 15 and 16 extend with their ends 16' and 15' within the guide channels. The plates 16 are of 95 100

comparatively heavy stock and rigid, while the plates 15 are of lighter elastic material so that they will act as springs. The ends 15' are normally deflected away from the adjacent ends 16' to be at an angle therewith, but when the ends are inserted in the guide channels they will be parallel, the ends 15' then frictionally engaging with and exerting spring pressure against the guide strips 19 and the ends 16' engaging against the outer edges of the deflected end section 18' of the strip 18. The screen side sections X extend a distance into the guide channels between the guide ends 15' and 16' of the guide plates. It is to be understood that the screen at its upper end within the receptacle B is subjected to the pull of a spring, but the frictional engagement of the ends of the rail bar with the guide strips will counteract such spring pull and will hold the screen in any position to which it has been adjusted.

Coming now to the locking or latching structure, the deflected outer sections 18' of the guide strips 18 terminate a distance short of the lower end of the guide strips 25 to leave recesses 24 below the shoulders or ends 25 into which the guide ends 16' are forced by the power of the spring ends 15' when the screen guide rail is moved into closing position against the window frame sill. The sections 18' of the strips 18 can be cut out at their lower ends to leave the recesses 24 or the lower sections 18'' of the strips can be bent outwardly to be straight, as clearly shown on Fig. 2.

Pushing of the ends 16' into the recesses 24 by the force of the spring ends 15' brings the ends 16' below the shoulders 25 against which the ends 16' will then abut to lock the screen against upward movement. As compensation or adjustment is frequently necessary for uneven sill surface, wear of the sealing felt 14, or other reasons, I preferably provide an adjustable latching abutment for the ends 16'. Such adjustable abutments are shown in the form of small rectangular plates or blocks 26 located within the guide channels 20 at the lower ends of the deflected sections 18' to extend a distance below the shoulders 25. The blocks are each held in adjusted position by a screw 27 extending through a vertical slot 28 in the respective guide strips and threading into the blocks. This permits the blocks to be readily vertically adjusted with their lower ends in proper position to detain or lock the ends 16' and thereby the rail bar and screen against opening movement after the screen has been pulled down to closed position. The abutment blocks preferably engage along their inner edges in the bends of the deflected sections 18' and the blocks are thus held in vertical position during adjustment thereof.

It will be noted that when pressure is applied to the fittings 17 as the screen is

closed, such pressure will tend to rotate or turn the rail bar on its longitudinal axis and such movement will swing the upper edges of the ends 16' forwardly and assist the spring ends 15' in locating such edges below the abutment blocks 26. Now, when it is desired to open the screen, lifting on the fittings 17 will rotate or turn the rail bar in the opposite direction and against the force of the spring ends 15', so that during the initial opening movement of the screen the guide plate ends 16' will be moved at their upper edges away from the abutment blocks so that further lift of the fittings 17 will then raise the screen. Special movement or manipulations to unlock the screen are therefore unnecessary, the lifting force on the fittings 17 accomplishing unlatching or unlocking of the screen automatically before the screen is raised. In Fig. 4 the normal position of the guide plates in the guide channels is shown, the guide plates being illustrated just above the latch or abutment plates. In Fig. 5 the rail bar is shown in locked position, and in Fig. 6 the rail bar is shown turned or rotated to unlatching position preparatory to opening of the screen. When the screen is closed, the felt sealing strip 14 is in intimate engagement with the window frame sill and as the abutment blocks 26 are adjustable, proper latching engagement between such blocks and the ends 16' can be maintained so that the felt strip will always make proper sealing engagement with the sill.

In Figs. 7, 8, and 9 a modified arrangement is shown in which U-springs 29 are used in place of the spring plates 15 in the structures shown in Figs. 1 to 6. These springs extend with their limbs vertical and each is secured with its front limb 30 against the rear side of the end 16' of the corresponding guide plate 16, and the springs may be secured as by means of rivets 31 shown, or by means of spot welding. As shown the springs are secured with their bends 32 at the bottom, and the other limb 33 of each spring engages against the guide strip 19 to exert the necessary spring action to create sufficient friction between the guide bar and guide strips to hold the screen in adjusted position. The limbs 33 of each spring are dished or have extensions for forming the end flange 34 and the side flanges 35. The flange 34 extends diagonally to form a bevel for reducing the friction at the spring end so that the spring will not bind. The side flanges 35 and particularly the inner flanges are at an angle corresponding with that of the deflected end 19' of the guide strip 19, engagement of the flanges with such ends serving to center the screen transversely of the window frame. The U-springs produce a resilient friction which will permit the screen to be readily raised and lowered and

which will hold it securely in adjusted position. When the guide bars reach the sill of the window frame the springs 29 will push the ends 16' of the guide plates 16 into the recesses 24 and into locking position below the detent plates 36. When pull is then applied to the fittings 17 the U-springs will give and permit the plates 16 to be readily released from the lock plates to permit opening of the screen.

Referring particularly to Fig. 2 it will be noted that the lower sections 18" of the guide strips 18 have their inner edges *a* a distance inwardly of the inner edges of sections 18', and when the screen is closed the guide bar clamping means 10 and 11 will engage along the edges *a* to secure the guide bar against transverse displacement in the window frame and to give a neat finished appearance. When the screen is raised there will be sufficient clearance between the ends of the clamping beams 10 and 11 and the edges of the sections 18' to prevent scraping of the beam ends against the guide strips.

To secure the guide strips against separation at the lower ends due to the pressure of the latch controlling spring 29, and also to form finished ends or ferrules for the guide strips, I provide shoes 36 of U shaped cross section for receiving the guide strips' ends as shown in Figs. 4, 5, and 6. These shoes also eliminate the necessity of cutting the guide strips accurately to length.

Other modifications may be made in structure and arrangement without departing from the scope of the invention.

I claim as follows:

1. In roller screen structure, the combination of a screen, a rail bar at the outer end of said screen, guide strips forming guide channels for said bar, guide members at each end of said bar extending into the adjacent guide channel and having friction engagement with the guide strips for holding the screen in adjusted position, each channel having a locking recess at its lower end for receiving one of the associated guide members when the screen is moved to closed position, and lift fittings on said bar having finger grip sections spaced in front of the bar whereby lift on said fittings will tend to rotate said bar on its longitudinal axis, rotation of the bar causing release of said guide members from said locking recesses and release of the screen for opening movement.

2. In a roller screen structure, the combination of a screen, a rail bar for the outer end of said screen, guide strips forming guide channels for each end of the bar, a guide member extending from each end of the bar into the adjacent channel, a spring member associated with each guide member within the corresponding channel yieldingly holding said guide member against the wall of the channel, an abutment at the

lower end of each channel and a recess therebelow into which the respective guide member is forced by the spring member into position below the abutment whereby said bar will then be locked when the screen is in closed position, and lifting means for said bar adapted upon application of lifting force thereto to cause rotation of the bar on its longitudinal axis and release of the guide members from said abutments to subsequently permit opening of the screen upon further lift of the lifting members.

3. In roller screen structure, the combination of a screen, a rail bar at the outer end of the screen, guide strips forming guide channels, a guide member at each end of the bar extending into the respective channel, a spring associated with each guide member for yieldably forcing it against one wall of the respective channel, a latch abutment at the lower end of each channel and a recess therebelow, said spring forcing said guide extension into said recess below said abutment when the screen is moved to closed position whereby said screen will be locked, pressure on said rail bar against the force of said spring releasing said guide bar from said latch abutment and permitting opening movement of the screen.

4. In roller screen structure, the combination of a screen, a rail bar at the outer end of the screen, guide strips forming guide channels for the ends of the bar, a pair of guide plates extending from each end of the bar into the respective channel, spring means forcing the guide plates of each pair apart into frictional engagement with the channel strips for holding the screen in adjusted position, and a latching abutment at the lower end of each channel past which one of said guide plates is moved whereby said bar will be latched against opening movement when the screen is moved to closed position, pressure against said bar away from said abutments causing release of the guide plates and permitting opening movement of the screen.

5. In roller screen structure, the combination of a screen, a rail bar at the outer end of the screen, guide strips forming a guide channel adjacent the end of the bar, a comparatively rigid guide extension at each end of the bar engaging in the respective channel against one wall thereof, an elastic guide member associated with each guide extension for engaging with the opposite wall of the respective channel, a latch abutment at the lower end of each channel past and below which the elastic guide member will force the guide extension to thereby latch the bar and screen against opening movement after closing thereof, and lift fittings on said bar for causing unlatching movement of said guide extensions prior to opening movement of the screen.

6. In roller screen structure, the combination of a screen, a rail bar, guide strips forming guide channels for the bar ends, latch mechanism for automatically locking the bar when the screen is moved into closed position, and means whereby said bar is released from the latch mechanism upon ro-

tational movement of said bar on its longitudinal axis prior to opening movement of the screen.

10

In witness whereof, I hereunto subscribe my name this 7th day of September, 1927.

WALTER H. LENISH.
